UNITED STATES PATENT OFFICE.

JOSEPH FARR, OF ST. CATHARINES, ONTARIO, CANADA.

TOY.

1,424,453.

Specification of Letters Patent. Patented Aug. 1, 1922.

Application filed April 18, 1921. Serial No. 462,140.

To all whom it may concern:

Be it known that I, JOSEPH FARR, a subject of the King of Great Britain, and a resident of the city of St. Catharines, in the county of Lincoln, in the Province of Ontario, Dominion of Canada, have invented certain new and useful Improvements in Toys, of which the following is a specification.

My invention relates to improvements in toys and the object of the invention is to devise a novel toy, which will provide fascinating entertainment and which may be cheaply produced.

My invention consists essentially of a box made to represent a model theatre and having a peep hole in the front end thereof and a stage opening near the rear end, a curtain bearing suitable legends or pictures located behind the stage opening, the ends of the curtain detachably connected to two suitably mounted rollers, a key for rotating the rollers and causing the curtain to move past the stage opening and a reflector located in an orifice in the roof of the box, all as herein-after more particularly described and illustrated in the accompanying drawings in which,

Fig. 1 is a general perspective, exterior view of my improved toy.

Fig. 2 is a plan view of my toy with the cover or roof removed.

Fig. 3 is a central vertical longitudinal section through my toy.

Fig. 4 is a transverse section on the line 4, 4 of Fig. 3, looking in the direction of the arrow.

Fig. 5 is a perspective view of the hinged rear end of my toy showing a bracket for mounting the curtain rollers.

Fig. 6 is a front view of one of the curtain rollers showing the manner in which the ends of the curtain are connected to the rollers.

Fig. 7 is an end view of Fig. 6.

Fig. 8 is a detail showing the end portion of one of the curtain rollers and the manner in which the operating key engages the roller.

Fig. 9 is a section on the line 9, 9 of Fig. 8.

Fig. 10 is a section through the side wall of my toy taken on the line 10, 10 of Fig. 3.

Fig. 11 is a rear view of a part of the imitation audience which I place in the theatre.

Fig. 12 is an end view of Fig. 11.

Like characters of reference indicate corresponding parts in the different views.

1 is my toy theatre which comprises a rectangular box having the floor 2, the sides 3 and 3¹, the front end 4, the rear end 5, 60 and the roof 6.

The exterior of the box is made to represent a model theatre by painting or otherwise marking doors, windows, and bulletin boards thereon (see Fig. 1). Imitation 65 chimneys 7 are also provided which may be made detachable for convenience in packing.

The front end 4 is provided centrally with a peep hole 8.

9 is a transversely disposed partition 70 within the box located towards the rear end thereof and is provided with the stage opening 10 therein.

The rear end 5 of the box is hingedly connected to the sides of the box by means of 75 the pins 11 and is adapted to fall rearwardly (see dotted lines to the right of Figs. 2 and 3).

Carried by the rear end 5 and extending inwardly therefrom is the channel shaped 80 bracket 12 comprising the side upright portions 13 and the front guide portion 14.

The side portions 13 are provided at their top and bottom ends respectively with the bearing notches 15 and 15¹ for a purpose as 85 will hereinafter appear.

16 are bent locking fingers journaled in the side uprights 13 and having their upper and lower bent portions 17 and 17¹ adapted to extend over the open ends of the bearing 90 notches 15 and 15¹ respectively.

The bracket 12 is so disposed that when the back 5 is in its normal raised position (see full lines in Figs. 2 and 3) the front face of the portion 14 lies adjacent to and 95 directly back of the stage opening 10 so as to act as a guide for the curtain as will presently be described.

18 are two tubular curtain rollers carrying the circular flanges 19 near each end and 100 each is provided with a longitudinal slot 20.

21 are journal portions of the rollers extending outwardly from the flanges 19.

22 is a flexible curtain having each end secured to a rod or enlargement 23 for a 105 purpose as will presently appear.

The partition 9 does not extend to the upper edge of the side walls of the box, and 24 is a supporting block carried by the inner face of the front end wall 4. 110

The roof 6 is loose and is inserted into the box so as to rest upon the block 24 and the top of the partition 9.

The roof 6 is provided with an orifice 25 into which is hingedly mounted a door 26.

27 is a mirror or other suitable reflector, carried by the under face of the door 26.

This door 26 is a snug fit in the orifice 25 so that it will remain in any set position.

16 The interior of the box is papered or otherwise decorated to resemble the interior of a theatre and the front face of the partition 9 would be decorated to resemble the stage.

15 Imitation rows of seats and persons sitting therein are made of paper and pasted to the floor. These imitation seats and audience are indicated by the numeral 28.

20 The side walls are provided with small orifices 29 which would be covered by the wall paper 30 on the inside of the box. On the wall paper and registering with the orifices 29 would be the representation of a lighting fixture indicated by the numeral 25 31 (see Fig. 3).

30 A further orifice 32 is provided in the roof which would likewise be covered by the paper on the inside of the roof and registering with this orifice 32 would be, on the paper, a representation of a lighting fixture for the ceiling such as a dome or cluster of lights.

35 The box is provided at one side thereof with two orifices 33 and 34 which register with the ends of the rollers 18 when the device is in the operative position (full lines Figs. 2 and 3).

40 35 is an operating key one end of which carries the lug 36. This end of the key is adapted to extend through the orifices 33 and 34 and to engage the hollow centre of the rollers 18, the lug 36 at the same time engaging the slot 20.

45 The construction and operation of my device is as follows;

In order to mount the curtain 22 into its operative position in the box, the back 5 is swung rearwardly into the dotted position (see Figs. 2 and 3). To do this it is 50 of course necessary that the key 35 be removed.

55 Each end of the curtain is now connected to one of the rollers 18 by slipping the curtain in through the slot 20 from the the outer end of the roller. In this operation the end rod or enlargement 23 carried by the end of the curtain passes into the centre bore of the roller. The curtain is now wound by hand as far as possible upon one 60 of the rollers 18. The width of the curtain is such that it lies between the two flanges 19 of the roller.

65 The rollers are now placed in position in the bracket 12. To do this the fingers 16 are turned outwardly so that the bent portions

17 and 17¹ are clear of the notches 15 and 15¹. The rollers are mounted so that the journal portions 21 engage the bearing notches 15 and 15¹ and the curtain passes forwardly in front of the guide 14. The 70 fingers are now turned inwardly so that the bent portions 17 and 17¹ lie over the open ends of the notches 15 and 15¹ and thus retain the rollers in position.

The back is then raised into its normal 75 upright position (full lines in Figs. 2 and 3).

In this position the curtain extends through the space between the rear of the partition 9 and the front of the portion 14, 80 which latter forms a guide over which the curtain passes.

In this position the ends of the rollers 18 register with the orifices 33 and 34 in the box so that the key 35 may be inserted to 85 engage either of the rollers desired.

90 It will be evident that the curtain may now be rolled from one roller 18 to the other by means of the key 35 and that in passing thus from roller to roller, it moves up or down as the case may be, across the stage opening 10.

If now, the observer look into the box through the peep hole 8 it is evident that as the key is turned the pictures or other matter 95 on the face of the curtain will be displayed to his view.

Further since the interior of the box is decorated and arranged to resemble a model theatre, with an audience assembled, the 100 novelty and picturesqueness of the device will be greatly increased.

In order to efficiently illuminate the curtain as it passes across the stage I provide a novel reflector in the roof of the box. 105

This consists of the trap door 26 carrying the mirror 27 on its under face. This door is hingedly mounted in the roof and may be tilted to any desired position and being a snug fit it will remain in any position set. 110

To use the device, the observer holds the box to the eye with one hand and adjusts the reflector 27 with the other hand until the light from a window or other source is brilliantly reflected upon the curtain. 115

The curtain is then moved past the stage by turning the key 35 by hand.

In order to still further increase the effect, the small orifices 29 are placed in the side walls of the box and at the points on the wall paper inside the box which register with these orifices are represented lighting fixtures. Also a larger orifice 32 is similarly treated in the roof and the representation of a dome light or cluster of lights is placed on 125 the ceiling paper.

It will be obvious, that since the interior of the box is dark, the representations of these lighting fixtures will be illuminated from the outside through the orifices 29 and 32 130

and the effect upon the observer, as he looks through the peep hole 8, will be that the theatre is illuminated by these lights.

In order to still further improve the appearance of the interior of the box and to make the resemblance to a theatre appear more realistic, I provide the imitation seats and audience 28. These are made of paper and are stuck to the floor of the box.

10 The curtain may be quickly and conveniently removed, and replaced by another curtain, by simply swinging the back 5 rearwardly and releasing the rollers by turning the bent portions 17 and 17¹ of the fingers 16. 15 This will permit the removal of the rollers and when a new curtain has been fitted to the rollers they are replaced in the bracket 12 as previously described.

10 The curtain will bear pictures or any other desirable display matter on its front face and any number of curtains may be used with one box.

From the foregoing it will be evident that I have devised a toy which will provide fascinating entertainment and one which may be cheaply produced.

What I claim as my invention is:

1. A toy of the class described comprising an enclosed rectangular box, having a peep hole in the front end thereof, and a removable rear end, an inwardly extending bracket carried by the rear end, a pair of transversely disposed rollers journalled in the bracket and situated adjacent to the top and bottom of the box, a flexible curtain having its ends connected respectively to the upper and lower rollers, the inner face of the bracket forming a guide over which the portion of the curtain extending between the rollers passes, the box having orifices which register with the ends of the rollers when the rear end of the box is in the normal position, an operating key adapted to extend through said orifices and to engage either of the rollers whereby said rollers may be rotated and the curtain wound from one roller to the other, a transverse partition within the box situated directly in front of the bracket and having an orifice therein, said orifice registering with the transversely disposed portion of the curtain, the interior of the box decorated to represent a theatre, and the front side of the transverse partition decorated to represent the stage thereof, the roof of the box having an orifice therein and a reflector adjustably mounted in said orifice whereby the light from outside may be reflected onto the portion of the curtain registering with the stage opening in the partition.

2. A toy of the class described comprising an enclosed rectangular box, having a peep hole in the front end thereof and a removable rear end, an inwardly extending bracket carried by the rear end, a pair of transversely disposed rollers detachably journalled in the bracket and situated adjacent to the top and bottom of the box, a flexible curtain having its ends connected respectively to the upper and lower rollers, the inner face of the bracket forming a guide over which the portion of the curtain extending between the rollers passes, the box having orifices which register with the ends of the rollers when the rear end of the box is in its normal position, an operating key adapted to extend through said orifices and to engage either of the rollers whereby said rollers may be rotated and the curtain wound from one roller to the other, a transverse partition within the box situ-

rollers when the rear end of the box is in the normal position, an operating key adapted to extend through said orifices and to engage either of the rollers whereby said rollers may be rotated and the curtain wound from one roller to the other, the roof of the box having an orifice therein and a reflector adjustably mounted in said orifice whereby the light from outside may be reflected onto the curtain within the box.

3. In a toy of the class described, the combination with a box made to represent a model theatre, and having a peep hole in the front end thereof, of a hingedly mounted rear end, an inwardly extending bracket carried by the rear end, a pair of transversely disposed rollers detachably journalled in the bracket and situated at opposite sides of the box, a flexible curtain having its ends detachably connected respectively to the two rollers, the inner part of the bracket forming a guide over which the portion of the curtain extending between the rollers passes, the box having orifices which register with the ends of the rollers when the rear end of the box is in its normal position, an operating key adapted to extend through said orifices and to engage either of the rollers whereby said rollers may be rotated and the curtain wound from one roller to the other, a transverse partition within the box situated directly in front of the bracket and having an orifice therein, said orifice registering with the transversely disposed portion of the curtain, the interior of the box decorated to represent a theatre, and the front side of the transverse partition decorated to represent the stage thereof, the roof of the box having an orifice therein and a reflector adjustably mounted in said orifice whereby the light from outside may be reflected onto the portion of the curtain registering with the stage opening in the partition.

4. In a toy of the class described, the combination with a box made to represent a model theatre, and having a peep hole in the front end thereof, of a hingedly mounted rear end, an inwardly extending bracket carried by the rear end, a pair of transversely disposed rollers detachably journalled in the bracket and situated at opposite sides of the box, a flexible curtain having its ends detachably connected respectively to the two rollers, the inner part of the bracket forming a guide over which the portion of the curtain extending between the rollers passes, the box having orifices which register with the ends of the rollers when the rear end of the box is in its normal position, an operating key adapted to extend through said orifices and to engage either of the rollers whereby said rollers may be rotated and the curtain wound from one roller to the other, a transverse partition within the box situ-

ated directly in front of the bracket and having an orifice therein, said orifice registering with the transversely disposed portion of the curtain, the interior of the box 5 decorated to represent a theatre with an audience assembled, and the front side of the transverse partition decorated to represent the stage thereof, the walls of the box provided with small orifices, and the portions 10 of the interior decorative covering of the box registering with these orifices bearing the representations of lighting fixtures, the roof of the box having an orifice therein and a reflector adjustably mounted in said orifice whereby the light from outside may be 15 reflected onto the portion of the curtain regis-

tering with the stage opening in the partition.

5. A toy of the class described comprising an enclosed box having its exterior made 20 to represent a model theatre and its interior decorated to represent the interior of a theatre, the walls of the box having a plurality of small orifices therethrough, the portions of the interior decorative covering of the 25 walls of the box which register with these orifices bearing the representations of lighting fixtures.
